GUN REST

Albert E. Sharp, New Canaan, Conn.

Application September 29, 1954, Serial No. 32,480

Term of patent 14 years

(Cl. D30—1)

FIG. 1

FIG. 2

Fig. 1 is a front view of a gun rest showing the new design;

Fig. 2 is a side view thereof with portions broken away for convenience of illustration; and

Fig. 3 is a plan view thereof.

The characteristic feature of the design resides in the rest portion having the configuration shown.

The invention claimed is:

The ornamental design for a gun rest, as shown and described.
